UNITED STATES PATENT OFFICE.

NORMAN MARSHALL, OF NEWTON, MASSACHUSETTS, ASSIGNOR TO GENERAL ELECTRIC COMPANY, A CORPORATION OF NEW YORK.

ADAPTER FOR LAMP-SOCKETS.

No. 825,228.

Specification of Letters Patent.

Patented July 3, 1906.

Application filed January 28, 1905. Serial No. 243,066.

To all whom it may concern:

Be it known that I, NORMAN MARSHALL, of Newton, in the county of Middlesex and State of Massachusetts, have invented certain new and useful Improvements in Adapters for Lamp-Sockets, of which the following is a specification.

The invention relates to adapters—such, for example, as are used for adapting incandescent lamp-sockets of the type known as "T-H" sockets—for use in connection with incandescent lamps of the Edison type.

It has been customary in supplying Edison lamps to use with T-H sockets to furnish an adapter for each lamp, which is applied to the T-H socket and is provided with terminals to coöperate with the terminals on the base of the Edison lamp. These adapters are provided with a screw-threaded nut forming a terminal for engaging the screw-threaded central terminal of the T-H socket and have been held in place in the socket merely by the engagement of these screw-threaded parts. In removing an old lamp from a socket the adapter is usually removed with the lamp, and it is necessary, therefore, to furnish an adapter for each Edison lamp which is to be used with a T-H socket, and this has been the usual practice.

The present invention relates to means for preventing the removal of the adapter after it has been once applied to a T-H socket, so that in removing the lamp the adapter cannot be removed, but remains as a permanent part of the T-H socket, thereby permanently transforming it into a socket adapted to receive Edison lamps. The device for preventing the removal of the adapter from the socket is so formed and arranged that it does not interfere with the application of the adapter to the socket, but will prevent the rotation of the adapter in a direction to unscrew the screw-threaded central terminals after the adapter has been once screwed into place.

For the purpose of illustration, I have shown in the accompanying drawings a T-H socket and an adapter embodying my invention in the forms in which I prefer to use them.

In the drawings, Figure 1 is an enlarged sectional view showing a T-H socket with an adapter applied to the socket. Fig. 2 is a further enlarged horizontal section through

the central terminal of the adapter looking downward on line 2 2, Fig. 1; and Fig. 3 is a similar view showing a modified form of means for preventing the removal of the adapter.

As shown in the drawings, the adapter is provided with the usual metallic screw-shell A for engaging the outer metallic screw-terminal of the lamp-base and is also provided with a central internally-screw-threaded nut B, forming the metallic terminal for engaging the screw-threaded terminal C of the T-H socket C'. The screw-threaded terminal B is secured in a disk D, of insulating material, secured within the upper end of the shell A. The upper end of the shell A is provided with a flat annular flange A', which forms the contact against which the switch-block of the key mechanism of the socket acts in the usual manner. The adapter is also provided with the usual insulating-sleeve F, surrounding the metallic screw-shell A.

As shown in Figs. 1 and 2, the means for preventing the removal of the adapter from the socket after it has been once screwed into place consists of a device in the form of a pin G, which normally projects into the bore of the central terminal B of the adapter. This pin is located in a recess b, formed in the wall of the terminal B, and is inclined in the direction of rotation of the adapter as it is screwed into the socket. The pin is tapered, as shown, and the walls of the recess b are correspondingly tapered, so that the inward movement of the pin is limited by its engagement with the walls of the recess. The pin is forced yieldingly forward by a wire spring H, arranged in an annular recess b' in the terminal B and bearing on the outer end of the pin.

The pin does not project into the bore of the terminal B sufficiently to prevent the screwing of the adapter onto the terminal C and by reason of its arrangement will yield when engaged by the screw-thread on the terminal C as the adapter is turned in the direction of the arrow, Fig. 2, in screwing the adapter into the socket. The pin rides on the screw-thread of the terminal C as the adapter is screwed into place. If now it is attempted to turn the adapter in the reverse direction, the pin will crowd forward, binding against the thread of the terminal C and preventing such rotation. Thus the pin pre-

vents the removal of the adapter after it has been once screwed into place without interfering with the application of the adapter to the socket.

5 The pin may be corrugated or roughened or provided with an edge or edges which will cut into or become embedded in the thread of the terminal C as force is applied to the adapter tending to turn it in a direction to unscrew it from the socket.

10 In Fig. 3, I have shown another form of device for preventing the removal of the adapter after it has been once screwed into place. In this form the pin G' is formed by the bent end 15 of an annular spring-wire H', arranged in a recess b² of the terminal B'. The pin in this case, as in the other, is inclined in the direction of the rotation of the adapter in applying it to the socket and normally projects somewhat into the bore of the terminal, but not 20 sufficiently to interfere with the screwing of the adapter into the socket. In this case the pin yields as the adapter is screwed into position, but binds on the screw-thread of the terminal C as soon as there is any tendency for 25 the adapter to turn in a reverse direction. The end of the pin in this case may be so shaped that it will cut into or become embedded in the thread of the terminal C when 30 force is applied to the adapter tending to unscrew it.

35 Although the present invention has been illustrated and described in detail as applied to T-H sockets, it is of course understood in its broader aspects the invention is applicable to sockets of other types.

40 Other forms and arrangement of the device for preventing the removal of the adapter may be employed without departing from the invention.

Without attempting to describe all such forms, what I claim, and desire to secure by Letters Patent, is—

45 1. An adapter for incandescent lamps provided with a screw-threaded terminal for engaging a complementary screw-threaded terminal of a lamp-socket, means for supporting an incandescent lamp, a pin inclined in the direction of movement of the adapter when

screwed into the socket, and means for yieldingly forcing the pin into proximity to the screw-threads on the adapter-terminal. 50

2. An adapter for incandescent lamps provided with an internally-screw-threaded terminal for engaging a complementary terminal on an incandescent-lamp socket, means for securing a lamp to the adapter, a pin mounted on the adapter and inclined in the direction of movement of the adapter upon being screwed into the socket, said terminal 60 having an annular groove, and an annular spring held in the groove in the terminal and yieldingly forcing the pin into the bore of the terminal. 55

3. An adapter provided with a central internally-screw-threaded terminal for engaging the central terminal of a lamp-socket, a metallic screw-shell, a pin inclined in the direction of movement of the adapter when being screwed into the socket, and means for 65 yieldingly forcing the pin into the bore of the adapter-terminal, substantially as described. 70

4. An adapter provided with a central internally-screw-threaded terminal for engaging the central terminal of a lamp-socket, a metallic screw-shell, a pin mounted in the terminal and inclined in the direction of movement of the adapter when being screwed into the socket, and an annular spring held in a groove in the terminal and yieldingly forcing the pin into the bore of the terminal, substantially as described. 75 80

5. An adapter provided with a central internally-screw-threaded terminal for engaging the central terminal of a lamp-socket, a metallic screw-shell, an annular spring H' embracing the adapter-terminal, a pin G' at the 85 end of the spring extending through the wall of the terminal in the direction of movement of the adapter when being screwed into the 90 socket, substantially as described. 95

In testimony whereof I have affixed my signature in presence of two witnesses.

NORMAN MARSHALL.
